UNITED STATES PATENT OFFICE.

HENRY TRUST, OF PARK RIDGE, NEW JERSEY, AND FRANK M. ASHLEY, OF BROOKLYN, NEW YORK; JOSEPHINE TRUST ADMINISTRATRIX OF SAID HENRY TRUST, DECEASED.

COUPLING.

Application filed June 16, 1920. Serial No. 389,341.

To all whom it may concern:

Be it known that we, HENRY TRUST, a citizen of the United States, and resident of Park Ridge, in the county of Bergen and State of New Jersey, and FRANK M. ASHLEY, a citizen of the United States, and resident of Brooklyn, in the county of Kings and State of New York, have invented certain new and useful Improvements in Couplings, of which the following is a specification.

Our invention relates to couplings for shafts and the object of our invention is to provide a coupling that is strong and durable and that may be readily coupled or uncoupled without the use of threads or screws and without being moved in a vertical direction relative to each other.

This coupling is designed especially for use with mixing and beating machines used in kitchens for preparing foods and a beater or ship is formed integral with the lower shaft.

Referring to the drawings which form a part of this specification:

Figure 1 is a vertical view, partly in section, of a coupling embodying our invention.

Figure 2 is a side view of the portion connected to the upper shaft.

Figure 3 is a cross sectional view showing a modified construction in which the key is formed separately instead of integral with one of the coupling elements.

A and B indicate, respectively, the two interlocking portions of the coupling and C indicates a ring by means of which the parts A and B are locked together. The portion B is provided with a keyway slot B' and the portion A is provided with a key A' formed integral and fitting the keyway B'. The exterior surface D of the portions A and B form a circle which the interior surface C' of the ring C closely contacts in holding the portions A and B together. The ring C extends below the lower end C² of the portion A and overlaps the lower end B² of the portion B to strengthen the construction as will be readily understood. A shoulder E is formed in the upper end of the portion A to support the ring C in position. A conical part A² is formed integral with the portion A and is provided with a threaded bore A³ to receive the shaft

F. The contacting surfaces G and G' respectively, are flat and therefore when the shaft F is rotated the shaft H is driven. By lifting the ring C, the portions A and B may be separated by moving part B laterally relative to the other part. The construction is such that the flat surface portions of elements A and B can be easily finished in a milling machine, or in cheap constructions the parts can be cast and thus provided at a very low cost. Referring to Figure 3, the portion B is formed with the keyway B' but a separate key I is fitted into a recess A⁴ formed in the portion A and extends into said keyway and serves the same function as that served by the key A', that is, to prevent the portion B from uncoupling by dropping out of the ring C.

Having thus described our invention, we claim as new and desire to secure by Letters Patent:

1. A coupling comprising two oppositely disposed portions each having a flat surface adapted to contact with the other and formed on the median vertical line of the coupling, one of which portions is provided with a transverse keyway formed in said surface and the other having a key extending into said keyway, and a ring adapted to slidably engage the exterior surfaces of said portions and hold them together, the said coupling portion being of considerably increased diameter relative to the shaft portions thereof to provide an enlarged contact surface between the coupling members.

2. A coupling comprising two oppositely disposed portions each having a flat surface adapted to contact with the other and formed on the median vertical line of the coupling, one of which portions is provided with a transverse keyway formed in said surface and the other having a key formed integral therewith and extending into said keyway, and a ring adapted to slidably engage the exterior surfaces of said portions and hold them together, the said coupling portion being of considerably increased diameter relative to the shaft portions thereof to provide an enlarged contact surface between the coupling members.

3. A coupling comprising two oppositely disposed portions each having a flat surface extending parallel with its exterior surface and adapted to contact with the other and

2

formed on the median vertical line of the coupling, one of which portions is provided with a transverse keyway formed in said surface and the other having a key extending into said keyway, and a ring adapted to slidably engage the exterior surfaces of said portions and hold them together, the said coupling portion being of considerably increased diameter relative to the shaft portions thereof to provide an enlarged contact surface between the coupling members.

4. A coupling comprising two oppositely disposed portions each having a flat surface extending parallel with its exterior surface and adapted to contact with the other and formed on the median vertical line of the coupling one of which portions is provided with a transverse keyway formed in said surface and the other having a key formed integral therewith and extending into said keyway, and a ring adapted to slidingly engage the exterior surfaces of said portions and hold them together, the said coupling portion being of considerably increased diameter relative to the shaft portions thereof to provide an enlarged contact surface between the coupling members.

5. A coupling comprising two oppositely disposed portions each having a flat surface adapted to contact with the other and formed on the median vertical line of the coupling, one of which portions is provided with a transverse keyway formed in said surface and the other having a key extending into said keyway, and a ring provided with an inwardly extending flange at its upper end and adapted to slidably engage the exterior surfaces of said portions and hold them together, the said coupling portion being of considerably increased diameter relative to the shaft portions thereof to provide an enlarged contact surface between the coupling members.

6. A coupling comprising two oppositely disposed portions each having a flat surface adapted to contact with the other and formed on the median vertical line of the coupling, one of which portions is provided with a transverse keyway and the other with a key extending into said keyway, each of said portions having one end formed cylindrical, and a ring encircling said portions and freely movable relative thereto, the said coupling portion being of considerably increased

increased diameter relative to the shaft portions thereof to provide an enlarged contact surface between the coupling members.

7. A coupling comprising two oppositely disposed portions each having a flat surface adapted to contact with the other and formed on the median vertical line of the coupling, one of which portions is provided with a transverse keyway and the other with a key extending into said keyway, each of said portions having one end formed cylindrical, and a ring having an inwardly extending flange at its upper end, said ring freely movable relative thereto, the said coupling portion being of considerably increased diameter relative to the shaft portions thereof to provide an enlarged contact surface between the coupling members.

8. A coupling comprising two oppositely disposed portions each having a flat surface adapted to contact with the other and formed on the median vertical line of the coupling, one of which portions is provided with a transverse keyway and the other with a key extending into said keyway, each of said portions having one end formed cylindrical, and a ring encircling said cylindrical end portions and freely movable relative thereto, the said coupling portion being of considerably increased diameter relative to the shaft portions thereof to provide an enlarged contact surface between the coupling members.

9. A coupling comprising two oppositely disposed portions each having a flat surface adapted to contact with the other and formed on the median vertical line of the coupling, one of which portions is provided with a transverse keyway and the other with a key extending into said keyway, each of said portions having one end formed cylindrical, and a ring encircling said cylindrical end portions and freely movable relative thereto and a shaft formed integral with one of said portions, the said coupling portion being of considerably increased diameter relative to the shaft portions thereof to provide an enlarged contact surface between the coupling members.

Signed at New York city in the county of New York and State of New York, this 10th day of June A. D. 1920.

HENRY TRUST,
FRANK M. ASHLEY.
